The A. C. Gilbert Company, New Haven, Conn.,
a corporation of Maryland

Application April 17, 1939, Serial No. 268,300

9 Claims.

(Cl. 246—246)

This invention relates to train operated circuit affecting devices of a type adapted for use in electric toy railway systems and particularly concerns a type of such device suited to association with electrified rails of a toy track in a manner to be operably engaged by some part of a passing toy train.

One object of the invention is to provide a circuit affecting device of this character adapted to coact with a traction wheel of the passing toy train.

Another object is to provide a device capable of coacting with a train wheel throughout a substantial distance of travel of the latter along the track.

Another object is to provide a device of this character which is free from any liability of derailing or otherwise interfering with the smooth riding of the train along the track.

A further object is to incorporate the working parts of such a device in a single unitary appliance capable of being quickly and removably installed as an attachment to the track structure without the necessity of lifting the trackage from its floor or table support surface and at arbitrary desired locations along the track.

A still further object is to incorporate in such a unit a binding post or binding posts suitable for the ready connection and disconnection of electric lead wires or electric circuit conductors which may be utilized in part for supplying current to, or tapping current from, the rail or rails of the toy track.

The invention further has as its object an embodiment of the aforementioned features in an assembled structure of extreme simplicity and low cost of manufacture.

These and related objects will appear in greater particular from the following description of a preferred construction illustrative of the nature of the improvements and in which description reference is had to the accompanying drawings, wherein:

Fig. 1 is a plan view drawn on a scale much larger than the usual actual size, of an electric contact shoe unit embodying the present invention.

Fig. 2 is a view taken in longitudinal cross section on the planes 2—2—2 in Fig. 1.

Fig. 3 is a side elevation looking at the unit of Fig. 1 in the direction of the arrows and showing fragments of the rails of a toy track and of one of the traction wheels of a toy train riding thereon.

Fig. 4 is a view looking upwardly at the bottom of the contact shoe unit.

Fig. 5 is a view taken in section crosswise of the track rails between the track supporting sleepers looking from the right toward the end of the wheel depressed contact shoe in Fig. 4.

Fig. 6 is a view similar to Fig. 5 showing the contact shoe in its normally elevated position in Fig. 2 when relieved of the weight of the train wheels.

Fig. 7 is a fragmentary view of one of the apertured end portions of the insulative base plate of the unit with the contact shoe removed to expose the shape of the aperture.

Fig. 8 is a fragmentary view of a portion of the structure in Fig. 3 showing a modified mounting for one binding post clip.

In Fig. 6 one of the usual sleepers 10 of an electric toy railway is shown extending crosswise under, and supporting, a traction rail 11 and a power or third rail 12. The latter rail in two-rail forms of toy track construction may comprise the other traction rail. Both rails are held downwardly against the top of the sleeper as usual by tongues 13 struck up out of the roof wall of the hollow sheet metal sleeper in a manner to overlap the foot flange 18 of the rail and be squeezed downwardly thereagainst. One or both of the rails may be separated from mechanical and electrical contact with sleepers 10 by separator facings 14 of insulative material such as thin sheet fibre. Additional tongues like 13 may of course be employed to secure the base flanges 18 to the sleeper at the opposite side of each rail but are omitted from the drawing for clarity.

All parts of my improved contact shoe appliance comprising a train actuated, track associated electrical control device, are mounted on an elongated base plate 15 which may be made of a strip of thick fibre or other suitably stiff insulative material. Base plate 15 has a aperture 16 near each of its ends shaped to produce the aperture contained tongue 17 as shown in Fig. 7.

The elongated metallic contact shoe 19 has turned-down ends 20 each containing a vertically elongated slot 21 occupied and guided by the tongue 17. Normally shoe 19 is kept elevated in the position shown in Figs. 2 and 6 by the up bearing ends of the bowed leaf spring 22 with the bottom ends of its slots 21 stopped by tongues 17, respectively. The lift spring 22 is preferably made of good electric conductive material, such as spring brass or phosphorus

bronze, and at its central portion is secured to the upper surface of base plate 15 by a suitable fastening means such as a hollow rivet or eyelet 23. Eyelet 23 also retains against the bottom surface of base plate 15 a binding post clip 24 of resilient conductive material adapted to trap the end of an electrical conductor or lead wire 25 as shown in Fig. 3. Clip 24 is prevented from swiveling about the eyelet 23 by means of its tongue 26 which projects upwardly into the material of the base plate. If needed, a similar tongue may extend downwardly from the leaf spring 22 into some loose fitting guiding aperture in the base plate 15 to prevent spring 22 from becoming longitudinally disaligned with contact shoe 19. Ordinarily however the eyelet 23 alone is sufficient to maintain the parts referred to in proper longitudinal alignment.

Between each end of the leaf spring 22 and the corresponding end 20 of the contact shoe, base plate 15 carries a pair of laterally and outwardly bowed, downwardly extending spring mounting arms 28 and 29, each clamped firmly against the bottom surface of base plate 15 by eyelets 30 and held from swiveling about its eyelet by a tongue 31 pocketed in the insulative material of the base plate. The eyelet 30 which secures one of the spring arms 29 may also be used to clamp between the latter and base plate 15 the mounting end of a second binding post clip 32 which may in all respects be like clip 24 except that it will preferably be shaped so that its movement in resiliently flexing to accommodate the attachment of a separate lead wire 35 will not interfere with the resilient flexing of the spring arm 29 when the latter is being forced past the rail flange for installing or removing the contact shoe.

Fig. 8 shows that binding post clip 32' may if preferred be independently secured to base plate 15 by a separate eyelet 33 and thereby removed from such mechanical proximity to spring arm 29 as might endanger interference in the respective performances of these two parts. The clip 32 as here shown remains in electrical contact with spring arm 29 by means of the extended length of its mounting end so that the latter still remains clamped between spring arm 29 and base plate 15.

Thus all metallic parts of the contact shoe unit, except only the spring detent arms 28 and 29, are held spaced from electrical contact with rails 11, 12, when the base plate 15 is placed between said rails and pressed downwardly against the foot flanges thereof. The entire appliance preferably has a length less than the distance between sleepers 10 in order not to interfere with the latter.

In installing the appliance at any selected location along the track, the mounting arms 28, 29 are forced to cam inwardly to their broken line positions in Fig. 6 when passing the relatively narrow space between the foot flanges of the rails and thereafter spring apart to their full line positions shown in Figs. 5 and 6 so that the base plate 15 brings up against the rail flanges with a sort of snap action and is yieldingly held there with considerable firmness by the four spring arms 28, 28 and 29, 29. It will be observed in Fig. 6 that one long edge of contact shoe 19 is thus positioned so closely to the traction rail 11 that the top surface of this shoe, being normally high enough, is engaged by the flange on the metallic conductive wheels 34 of the locomotive or other unit of a toy train and thereby pressed

downwardly by the weight of the locomotive or train unit to its position shown in Figs. 3 and 5 as the wheel rolls along the stretch of track where the shoe is located. Spring 22, of course, is weak enough to yield downwardly to the weight of the locomotive or of any car of the train without lifting it from the rail. Thus the metal of wheel 34 electrically bridges contact shoe 19 and the traction rail 11 and completes the circuit from binding post clip 24 to binding post clip 32, this circuit including eyelet 23, lift spring 22, contact shoe 19, wheel 34, track 11, and spring arm 29. The broken line position of contact shoe 19 in Fig. 3 shows that the shoe is capable of tilting freely as well as being free to move up and down.

In use, my improved contact shoe appliance in the form illustrated and described, as well as in forms differing therefrom in detail, may be set down as a unit between the rails at any selected 20 location in a system of toy electric railway track to produce any desired electric circuit controlling effect when the toy train arrives at or passes said location. It will be understood that the electric 25 circuit affected by the appliance may contain a source of current supply together with electrically operable signal lights, train whistles, bells, or apparatus for starting or stopping the train itself by controlling the supply of current to its track or any cycle of track switching or other electrically producible effect in toy railway system apparatus and appurtenances capable of enhancing the realism of the performance of the elements employed in the system.

Obvious substitutions and departures from the exact construction herein disclosed may be made without exceeding the scope of this invention and the following claims are intended to cover all such substitutions and departures which fairly 40 fall within their terms:

I claim:

1. The combination with flanged rails of an electrified toy track for toy trains, of an electrical contact making appliance adapted for readily 45 removable attachment to said track, including a movable electrical conductive element constructed and arranged to project retractably into the path of travel of some portion of a toy train riding along said track, and a base structure carrying said element and spanning the space between the nearest flanges of respectively adjacent track rails and overlying and resting on the top surfaces of said flanges and insulated from one of said rails, together with means carried by said 50 base structure constructed and arranged releasably to hook under one or more of the said rail flanges in a manner to hold said structure in stationary position seated on the top surface of said flanges.

2. The combination defined in claim 1, in which the said electrical conductive element comprises a compressible continuous elongated stiff strip of conductive material horizontally superimposed over and spaced above the said mounting base 55 and having downward disposed ends extending past said base to below the level of the said rail flanges, together with means carried by said mounting base to engage with and limit upward movements of said strip ends and a spring constructed and arranged to urge said strip constantly upward.

3. The combination with flanged rails of an electrified toy track for toy trains, of an electrical contact making appliance adapted for readily 75 removable attachment to said track, including a

movable electrical conductive element constructed and arranged to project retractably into the path of travel of some portion of a toy train riding along said track, and a plate-like mounting base of insulating material wide enough to span the space between the nearest flanges of respectively adjacent track rails and to overlie the top surfaces of said flanges while narrow enough to clear all other nearest together portions of said respectively adjacent rails so as to be passable between said other portions to and from a position resting on the top surfaces of said flanges, together with means carried by said base projecting downward therefrom in a direction to hook under the bottom of at least one of said rail flanges in a manner releasably to hold said structure stationary in its said position.

4. A circuit affecting appliance to be detachably mounted on rails of a toy electric track system, embodying a unitary assemblage of parts, including a stiff elongated base plate of electrical insulative material having a width adapted to bridge the space between and overlap the foot flanges of spaced track rails, resilient detent devices carried by said base plate constructed and arranged to engage with said foot flanges in a manner to hold said plate firmly but removably seated thereon, a stiff elongated shoe of electrical conductive material, and means to support said shoe resiliently above said base plate in a manner to permit the shoe to be depressed in relation to said base plate.

5. A circuit affecting appliance to be detachably mounted on flanged rails of a toy electric track system, embodying a unitary assemblage of parts, including a stiff elongated base plate of electrical insulative material having a width adapted to bridge the space between and overlap the foot flanges of spaced track rails, spring arms carried by said base plate and bowed laterally outward in respectively opposite directions to a greater spacing than said space between said rail flanges in a manner to latch into holding engagement with the edges of said rail flanges when the appliance is pressed downward to a seated position upon said flanges, a stiff elongated shoe of electrical conductive material, and means to support said shoe resiliently above said base plate in a manner to permit the shoe to be depressed in relation to said base plate.

6. A circuit affecting appliance for toy electric railway systems embodying a unitary assemblage of parts including a stiff elongated base plate of electrical insulative material having longitudinally spaced U-shaped apertures each affording a guide tongue, a stiff elongated shoe of electrical conductive material having downward turned opposite ends passing through said apertures respectively and each containing a slot elongated in a direction substantially perpendicular to the plane of said base plate and engaged by one of the said guide tongues in a manner to limit movement of said shoe away from said base plate, and means to support said shoe resiliently above said base plate in a manner to permit the shoe to be depressed relative thereto.

7. A circuit switching appliance for releasable attachment to a toy railway track having rails with conventional foot flanges and adjoining webs upstanding respectively therefrom, including an electrical contact device for completing an electric circuit, a rigid base structure adapted to overlap and rest upon the web adjoining surfaces of the said foot flanges of two of said rails and carrying said device positioned adjacent to one of said rails and including electrical insulative material, and resilient detent devices carried by said base structure projecting downward therefrom and constructed and arranged to spring automatically into and out of holding engagement with underneath portions of said foot flanges of the track rails as a consequence of the mere movements of said base structure respectively to and from a position seated against the web-adjoining surfaces of said flanges.

8. An electrical contacting unit for use with toy electric trains and track, embodying in combination, an elongated stiff thin electrical insulative card adapted for assemblage with electrified toy track, a stiff flat strip of conductive metal bare and exposed on each of its opposite faces and extending alongside said card in spaced relation thereto said strip having bent-over end portions extending into guiding engagement with said card, a leaf spring arranged between said card and strip in a manner to press conductively and slidably at two longitudinally spaced points against one of said bare strip faces in a manner urging the strip away from the card and leaving the other bare face of said strip free to be wiped tilted and depressed by a toy train in passing, a fastener securing said leaf spring to the face of said insulative card nearest the said conductive strip and penetrating said card, and a binding post for electrical connections secured to the opposite face of said card by said fastener.

9. An electrical contacting unit for use with toy electric trains and track, embodying in combination, an elongated stiff thin electrical insulative card adapted for assemblage with electrified toy track, a stiff flat strip of conductive metal bare and exposed on each of its opposite faces and extending alongside said card in spaced relation thereto said strip having bent-over end portions extending into guiding engagement with said card, an elongated single bowed leaf spring having its opposite extremities free and arranged between said card and strip in such manner that said extremities press conductively and slidably at two longitudinally spaced points respectively against one of said bare strip faces in a manner urging the strip away from the card and leaving the other bare face of said strip free to be wiped tilted and depressed by a toy train in passing, said bowed spring being secured at its mid portion to said insulative card whereby flexure of said spring when deflected by movement of said strip toward said card causes said free extremities of the spring to rub somewhat against the face of said strip.

MARSHALL H. FRISBIE.
